(57) CLAIM

The ornamental design for a deluxe tricycle, as shown and described.

DESCRIPTION

The nature and intended use of the article in which the design is embodied is that of a small vehicle for children and the like.

FIG. 1 is a perspective view of a deluxe tricycle, with a handle partially extended, showing my new design;

FIG. 2 is a rear view thereof;

FIG. 3 is a front view thereof;

FIG. 4 is a side view thereof;

FIG. 5 is a bottom view thereof;

FIG. 6 is a perspective view thereof, with the handle fully extended; and,

FIG. 7 is a perspective view thereof, with the handle removed for the clarity of illustration.
